DESIGN FOR A COLLOID MILL OR SIMILAR ARTICLE

William McLean and Albert Hulley, Geneva, N. Y.

Application December 26, 1941, Serial No. 104,864

Term of patent 14 years

To all whom it may concern:

Be it known that we, William McLean, a citizen of the United States, and Albert Hulley, a citizen of Canada, and both residents of Geneva, in the county of Ontario and State of New York, have invented a new, original, and ornamental Design for a Colloid Mill or Similar Article, of which the following is a specification; reference being had to the accompanying drawing, forming part thereof.

Fig. 1 is a top plan view of a colloid mill or similar article, showing our new design.

Fig. 2 is a side elevational view thereof.

Fig. 3 is a front elevational view thereof.

We claim:

The ornamental design for a colloid mill or similar article, substantially as shown.

WILLIAM MCLEAN.
ALBERT HULLEY.
